AUTOMOBILE HEADLIGHT

Filed Jan. 6, 1927

INVENTOR.

David W. Ohaiver,

Al B. Ford
ATTORNEY.

UNITED STATES PATENT OFFICE.

DAVID W. OHAVER, OF ROCKVILLE, INDIANA.

AUTOMOBILE HEADLIGHT.

Application filed January 6, 1927. Serial No. 159,324.

My said invention relates to headlights for automobiles or other vehicles and it is an object of the invention to provide a headlight capable of illuminating the roadway both ahead of and to the sides of a vehicle upon which the same is mounted without glaring or blinding the eyes of the driver of an approaching vehicle or the eyes of a person looking directly at such light.

10 Referring to the accompanying drawings, which are made a part hereof and on which similar reference characters indicate similar parts,

15 Figure 1 is a central longitudinal vertical section,

Figure 2, a fragmentary section taken on line 2—2 of Figure 1,

Figure 3, a modified form of reflector.

In the drawings reference character 10 20 indicates a casing or shell having a hollow support 11 for attachment to a part of the vehicle and by means of which the headlight is adapted to be supported. A socket 12 is mounted on the casing 10 and such 25 socket is provided with conductors 13 which extend to a light bulb 14. If preferred the conductors 13 may be inserted through the support 11 instead of as shown. The casing or shell 10 is preferably parabolic in form 30 and the reflector 15 is of conical shape and is adapted to be mounted within the same, such reflector being provided with an annular flange 16 which engages the end of the casing. The casing or shell 10 is provided 35 with an overhanging shell 17 which is of substantially the same depth as the casing 10 but covers substantially only the upper half of the lamp, the lower half of which is provided with a lens 18 of transparent material 40 which permits light to be reflected there-through. The overhanging shell is provided with an inwardly extending flange 19 which supports an external flange 20 on the lens 18. The casing 10 is provided with a plurality of forwardly extending fastening elements or fingers 21, one being disposed preferably at each side and one at the top of the same, and through which fastening screws 22 extend into the casing 17 for se-

50 curing said casing and the lens in position. A substantially parabolic reflector 23 is mounted in the overhanging casing 17, such reflector being provided with an aperture at its central portion in which is mounted the 55 cylindrical part of the lamp or bulb 14 adapted to be clamped in position by means

of a set screw 24. As will be observed from Fig. 1 the reflector 23 is so arranged as to project the light upon the conical reflector 15 from whence it will be reflected through the forward, side, and bottom portions of the lens 18. On account of the particular manner of mounting the light 14 within the reflector 23 it may be moved toward and from the conical reflector 15 and in order 60 to vary the inclination of the reflector 23 I preferably mount the same on a yoke 25 which has one end mounted in a bracket 26 at one side of the overhanging shell 17 while its opposite end projects through the opposite end of said shell and is provided with a knurled operating knob 26. Also a lock nut 27 is provided for locking the yoke 25 and reflector carried thereby in the proper 65 adjusted position. By means of this yoke 70 the reflector and light may be swung about the axis of the yoke and the angle at which the light shines upon the reflector will be varied accordingly. In lieu of the parabolic reflector 23 shown in Fig. 1 a conical reflector 28, such as shown in Fig. 3, may be 75 used.

If desired the forward section of my light may be applied to a conventional headlight with or without the substitution of a conical 80 reflector, however, I have found it advantageous to use a conical reflector as I have shown. With the structure illustrated the light from the bulb 14 will shine directly 85 on the conical member 15 and will be reflected onto such reflector by the parabolic reflector 23 and from such a conical reflector the light will be projected ahead through the lens 18 below flange 19 and downwardly on the roadway and on the adjacent territory 90 at the sides of the roadway.

With the foregoing device light will not 95 shine above a horizontal plane so that it will blind the eyes of a driver of an approaching vehicle or other person looking directly at the same but will efficiently perform the function for which is is designed.

It will be obvious to those skilled in the art that various changes may be made in my device without departing from the spirit 100 of my invention and therefore I do not limit myself to what is shown in the drawings and described in the specification but only as indicated in the appended claims.

Having thus fully described my said invention, what I claim as new and desire to 105 secure by Letters Patent, is:

1. A headlight comprising an elongated oval-shaped casing, a transparent lens forming substantially one-fourth of said casing at the lower forward portion of the same, a 5 conical reflector mounted opposite said lens in a position to project light through said lens, an auxiliary reflector mounted above said lens in opposed relation to said conical reflector, and a source of light in said auxiliary reflector adapted to have its rays projected onto the conical reflector and through the lens, said auxiliary reflector being pivotally supported on a transversely disposed pivot whereby the same may be swung about 10 the same, substantially as set forth.

2. A headlight comprising an elongated oval-shaped casing having a curved detach-

able overhanging forward half-section, a lens for said headlight, said overhanging half-section and said lens being complementarily formed and curved in conformity with the casing, a conical reflector mounted within said casing, a source of light in said casing, a yoke journaled in the sides of said overhanging half-section, and a reflector 20 carried by said yoke whereby the same may be adjusted above the horizontal axis of the conical reflector, substantially as set forth.

In witness whereof, I have hereunto set my hand at Indianapolis, Indiana this 4th 25 day of January, A. D. nineteen hundred and twenty-seven.

DAVID W. OHAVER.
